UNITED STATES PATENT OFFICE

98,366

DESIGN FOR A CHEST OR SIMILAR ARTICLE

Marshall C. Pumphrey, Los Angeles, Calif., assignor to Barker Bros. Incorporated, Los Angeles, Calif.

Application November 12, 1935, Serial No. 59,506

Term of patent 3½ years

To all whom it may concern:

Be it known, that I, Marshall C. Pumphrey, a citizen of the United States, residing at Los Angeles, county of Los Angeles, State of California, have invented a new, original, and ornamental Design for a Chest or Similar Article, of which the following is a specification, reference being had to the accompanying drawing, forming part thereof. The figure is a perspective view of a chest or similar article, showing my new design.

The end of the chest not shown in the drawing is identical in design with the end which the drawing illustrates.

I claim:

The ornamental design for a chest or similar article as shown and described.

MARSHALL C. PUMPHREY.
